EDUCATIONAL TOY VEHICLE

Marvin I. Glass, Chicago, Howard J. Morrison, Highland Park, and Bette M. Kaelin, Chicago, Ill., assignors to Marvin Glass & Associates, Chicago, Ill.

Filed Feb. 17, 1972, Ser. No. 227,311

Term of patent 14 years

Int. Cl. D21—01
U.S. Cl. D25—1 R

Fig. 2

Fig. 5

FIG. 1 is a front perspective view of an educational toy vehicle showing our new design;

FIG. 2 is an enlarged scale top plan view thereof;

FIG. 3 is an enlarged scale left side elevational view thereof, the right side being a mirror image thereto;

FIG. 4 is an enlarged scale front elevational view thereof;

FIG. 5 is an enlarged scale rear elevational view thereof; and

FIG. 6 is an enlarged scale bottom plan view thereof.

We claim:

The ornamental design for an educational toy vehicle, substantially as shown and described.
